UNITED STATES PATENT OFFICE

JAMES H. WATSON, JR., OF BRONXVILLE, NEW YORK.

DESIGN FOR A TOBACCO-POUCH.

51,247.

Specification for Design.

Patented Sept. 4, 1917.

Application filed July 5, 1917. Serial No. 178,878. Term of patent 7 years.

To all whom it may concern:

Be it known that I, JAMES H. WATSON, Jr., a citizen of the United States, residing in Bronxville, Westchester county, State of New York, have invented a new, original, and ornamental Design for a Tobacco-Pouch, of which the following is a specification, reference being had to the accompanying drawing, forming part thereof.

Figure 1 is a perspective view of the to-

bacco pouch,—Fig. 2 is a rear elevation of the same.

I claim:

The ornamental design for a tobacco pouch, as shown.

JAMES H. WATSON, JR.
